DESIGN FOR A COMBINED SAXOPHONE NECK, MOUTH PIPE FASTENING AND MOUTHPIECE KEY

Earl J. Gillespie, Elkhart, Ind., assignor to The
Martin Band Instrument Company, Elkhart,
Ind., a corporation of Indiana

Application February 23, 1945, Serial No. 118,104

Term of patent 14 years

(Cl. D56—1)

To all whom it may concern:

Be it known that I, Earl J. Gillespie, a citizen of the United States, residing at Elkhart, in the county of Elkhart and State of Indiana, have invented a new, original, and ornamental Design for Combined Saxophone Neck, Mouth Pipe Fastening and Mouthpiece Key, of which the following is a specification, reference being had to the accompanying drawing, forming a part thereof.

In the drawing:

Figure 1 is a side elevational view of a com-

bined saxophone neck, mouth pipe fastening and mouthpiece key, showing my new design.

Figure 2 is a front elevational view of Figure 1;
Figure 3 is a top plan view of Figure 1; and
Figure 4 is a bottom view showing the underneath portion of the saxophone neck.

I claim:

The ornamental design for a combined saxophone neck, mouth pipe fastening and mouthpiece key, substantially as shown.

EARL J. GILLESPIE.
